UNITED STATES PATENT OFFICE

1,997,247

LOADING MACHINE

Frank Cartlidge, Chicago, Ill., assignor to Goodman Manufacturing Company, Chicago, Ill., a corporation of Illinois

Original application August 2, 1930, Serial No. 472,701. Divided and this application December 14, 1931, Serial No. 580,756. Renewed July 13, 1934

25 Claims. (Cl. 198—8)

This invention relates to improvements in truck mounted material gathering and loading machines particularly adapted for loading coal at the working face of a mine, wherein the gathering element is extensible into and retractable from the coal independently of movement of the supporting truck and has among other objects to provide a new and improved means of a simplified construction for extending the gathering and loading element into or retracting said gathering and loading element from the coal.

My invention may be more clearly understood with reference to the accompanying drawings wherein:

Figure 1 is a side elevation of a machine constructed in accordance with my invention;

Figure 2 is a plan view of the device shown in Figure 1;

Figure 3 is an enlarged side elevation of the embodiment of my invention shown in Figure 1, with parts broken away and in section;

Figure 4 is a partial fragmentary enlarged detail side elevation of the forward portion of the embodiment of my invention shown in Figure 1, with parts broken away and in section to more clearly show the details thereof;

Figure 5 is a sectional view taken substantially on line 5—5 of Figure 4;

Figure 6 is a sectional view taken substantially on line 6—6 of Figure 4;

Figure 7 is a sectional view taken substantially on line 7—7 of Figure 4;

Figure 8 is a sectional view taken substantially on line 8—8 of Figure 4; and

Figure 9 is a detail view of a portion of the mechanism for operating the clutches on the device of my invention.

Like numerals refer to like parts throughout the various figures.

Referring now in particular to the drawings, the main elements of the embodiment of my invention illustrated consist of a wheeled truck or main frame 10 having an inclined gathering and loading element 11 in front of said main frame, and a discharge conveyor 12 extending from beneath the rear end of said gathering and loading element and upwardly and rearwardly therefrom overhanging the rear end of said main frame for discharging material into suitable receptacles such as mine cars.

Suitable means are provided for driving the main operating parts, which means herein comprises an electric motor 13. Said electric motor has driving connection with the truck wheels for driving the loading machine about the mine and

for feeding the loading element 11 into the material to be loaded. Said electric motor also serves as a driving means for the operating parts on the gathering and loading element 11, for raising or lowering said gathering and loading element, for swinging said gathering and loading element about a vertical axis, and for extending said loading element into or retracting said loading element from the material which is being loaded. The details of the drive to the main operating parts are similar to those disclosed in my aforementioned prior application so will not herein be described in detail.

The gathering and loading element 11 comprises an inclined conveyor frame 14 supported between a pair of upright side plates 15 for pivotal movement with respect thereto about a horizontal axis disposed adjacent the rearward end thereof. The upright side plates 15 are in turn supported on the main frame 10 for swinging the inclined conveyor frame 14 about a vertical axis. The means for swinging the upright side plates 15 about a vertical axis, and the inclined conveyor frame 14 about a horizontal axis, are not herein shown in detail nor described since they are no portion of my present invention and are fully disclosed in my aforementioned prior application.

The inclined conveyor frame 14 extends forwardly from its axis of pivotal connection to the upright side plates 15 and comprises side plates 16 arranged adjacent opposite sides thereof and a bottom pan 17 tying said side plates together. The side plates 16 are inclined outwardly and upwardly from the top portion thereof to provide a means for deflecting material onto the bottom pan 17 of the conveyor frame 14 during movement upwardly therealong.

A suitable conveying means is carried by the inclined conveyor frame 14 which may be of any suitable construction but which is herein shown as being a flight conveyor 18 comprising endless chains 19 having flights 20 supported therebetween in a usual manner. The endless chains 19 are trained around suitable direction changing devices on a transversely extending shaft 21 at the forward end of the inclined conveyor frame 14 along the top side of the bottom pan 17 to and around suitable drive sprockets on a transversely extending drive shaft 22. Said shaft is journaled in said conveyor frame and the side plates 15 and is coaxial with the axis of pivotal connection of said conveyor frame to said side plates. From thence the endless chains 19 are trained around suitable guides beneath the bottom pan 17 under idler sprockets 23 and over drive

sprockets 24. Said last-named sprockets are keyed on opposite ends of a transversely extending shaft 25 journaled in a forwardly extending frame member 26. Said frame member is 5 slidably mounted on said conveyor frame and supports a gathering or conveying element indicated at 27. From the sprockets 24 said chains extend to and around the aforementioned direction changing devices on the transversely extending shaft 21.

10 The transversely extending drive shaft 22 is driven from the motor 13 by means of a suitable geared reduction and a chain and sprocket drive indicated at 28 in a manner similar to the manner 15 in which the conveyor is driven in my aforementioned prior application.

15 The gathering element 27 is of a construction similar to that shown in my aforementioned prior application and includes an inclined apron 29 extending forwardly of and to each side of the inclined conveyor frame 14 and having a ground 20 engaging surface 30. As herein shown said apron is inclined at an acute angle with respect to the conveyor frame 14 and at a greater angle of 25 incidence to the ground upon which the machine rests than said inclined conveyor frame. Suitable gathering mechanism is supported on the inclined apron 29 which may be of any construction, but which is herein preferably shown as 30 comprising gathering arms 31 supported on suitable endless chains guided for movement in an orbital path along guide members 33 disposed along each side of said inclined conveyor frame in a usual manner.

35 Referring now in particular to the means for extending and retracting the gathering element with respect to the inclined conveyor frame 14, the forwardly extending frame member 26 is supported on said inclined conveyor frame for 40 slidable movement with respect thereto and is moved along said conveyor frame by power means actuated by the endless chains 19 and drive sprockets 24.

45 The forwardly extending frame member 26 is constructed so as to be slidable along the inclined conveyor frame 14 and both sides of said frame member are substantially the same so one side only is herein shown in detail. As herein shown the forwardly extending frame member 26 comprises side plates 32 arranged along the outer 50 sides of the side plates 16 and having outwardly flared upper portions 34 extending beneath the outwardly flared upper portions of the side plates 16. Portions 35 are herein shown as being 55 secured to the upper surface of the outside of the flared portions 34 and extend upwardly and inwardly from said outwardly flared upper portions along the top side of the outwardly flared portions of the side plates 16. Bearing strips 36 are 60 provided between the under surface of the portions 35 and the upper surface of the outwardly flared portion of the side plates 16 to permit slidable movement of the portions 35 along the outwardly flared portion of the side plates 16. 65 Likewise, bearing strips 37 are secured to the top side of the outwardly flared upper portions 34 of the side plates 32 and are adapted to slidably engage the underportion of the outwardly flared portion of the side plates 16.

70 Gibbed members 39 are fixed to the outer side of the side plates 16 adjacent the upper portion thereof in such a manner that the gibs of said gibbed members extend upwardly along and are spaced from the side plates 16. The gibs of said 75 gibbed members are adapted to be engaged by

suitable slots formed in the under surface of members 40 fixed to the inner side of the side plates 32. Angles 41 are attached to the inner sides of the side plates 32 on one leg. The other legs of said angles extend inwardly from said side plates and are engageable with the upper surface of racks 42 extending longitudinally of the inclined conveyor frame 14. The racks 42 are connected to the outer side plates 16 of said inclined conveyor frame in a suitable manner, 10 such as cap screws indicated at 43, and have their teeth extending downwardly therefrom. It may thus be understood that the gathering element 27 and forwardly extending frame member 26 15 may be slidably moved along the inclined conveyor frame 14.

15 Referring now in particular to the means for slidably moving the gathering element 27 and forwardly extending frame member 26 along the inclined conveyor frame 14 for extending said 20 gathering element into the material it is desired to load or for retracting said gathering element therefrom, bevel pinions 45 are keyed on opposite ends of the transverse shaft 25 and mesh with and drive bevel gears 46 keyed on shafts 25 25 47 disposed perpendicularly to the inclined apron 29. Said shafts extend upwardly from said bevel gears and have their upper portion journaled in suitable bearing means adjacent the underportion of said apron. Sprockets 48 are keyed 30 to the upper end of said shafts for driving the gathering arms 31 in orbital paths about the guide members 33.

35 A bevel gear 49 is keyed on the right hand shaft 47 intermediate the ends thereof. Said bevel gear meshes with and drives a bevel pinion 50 keyed on a shaft 52 extending longitudinally of the forwardly extending frame member 26 and disposed in a plane parallel to the plane of said longitudinally extending frame 40 member. The shaft 52 is journaled in a bearing member 53 rearwardly of the bevel pinion 50 and has an end 54 opposite said bevel pinion which is rotatably supported within a suitable socket in a member 55. Said member has a shaft portion 56 extending rearwardly therefrom which is journaled within suitable bearing supports on the forwardly extending frame member 26. Said member has a portion 57 which serves as a casing for a planetary gear reduction device 58 for 50 driving the shaft portion 56 from the shaft 52 in one direction at one speed or in an opposite direction at another speed without reversal of said shaft.

55 Referring now in particular to the means for driving the shaft portion 56 of the member 55 from the shaft 52, a sun gear 59 is keyed on the shaft 52 forwardly of the member 55 and meshes with and drives planetary pinions 60. Said pinions are journaled on studs 61 supported within 60 a cage 62, which cage is provided with a hub 63 rotatably supported on the shaft 52. An internal gear 64 is keyed within the casing portion 57 of the member 55, which internal gear meshes with and is driven by the planetary pinions 60.

65 The hub 63 is provided with teeth 65 on its outer periphery, which teeth mesh with teeth cut on the inner periphery of a clutch member 66. Said clutch member is provided with forwardly extending clutch jaws 67 which are adapted to mesh with clutch jaws 69 integral with the bearing member 53.

70 Thus when the clutch jaws 67 mesh with the clutch jaws 69, the cage 62 is held from rotation. This causes the sun gear 59 to rotate the plan- 75

etary pinions 60 upon rotation of the shaft 52 which in turn drives the internal gear 64 and member 55 in one direction at a slower speed than the speed of rotation of said shaft.

5 The clutch member 66 is also provided with inwardly extending clutch jaws 70 which are adapted to mesh with clutch jaws 71 formed integral with the shaft 52. Thus upon rotation of the shaft 52 when the clutch jaws 70 mesh with the clutch jaws 71 the cage 62 is rotated at the speed of rotation of the shaft 52 which in turn drives the member 55 at the speed of rotation of said shaft in a direction opposite to the direction of rotation of said member when the clutch 10 jaws 67 are engaged with the clutch jaws 69 in an obvious manner.

It may thus be seen that the member 55 may be rotated at a slow speed in one direction or at a higher speed in an opposite direction without 15 reversal of the endless chains 19 or shaft 47, and that when the clutch jaws 67 and 70 of the clutch member 66 are disengaged from the clutch jaws 69 or 71 that rotation of the member 55 will be stopped when said member is under a load. 20 Suitable means are provided for shifting the clutch member 66 which will hereinafter be referred to.

A worm 72 is keyed on the shaft portion 56 of the member 55 and meshes with and drives a worm gear 73. The worm gear 73 is freely mounted on a shaft 74 which extends transversely of the forwardly extending frame member 26 and the inclined conveyor frame 14. A member 75 abuts and is fixed to the outer side of the worm 25 gear 73 in a suitable manner and is provided with an aperture 76 therein. A drive collar 77 is keyed on the outer end of the shaft 74 and abuts the outer face of the member 75. The drive collar 77 is provided with a shearing pin 78. Said pin 30 is adapted to engage the aperture 76 in the member 75 and is secured to the drive collar 77 by means of a suitable set screw 79.

It is thus seen that the shaft 74 is driven by the worm gear 73 through the member 75, shearing pin 78, and drive collar 77 and that when an overload is imposed upon the shaft 74 the shearing pin 78 will break which will prevent breakage of the drive gearing.

Drive pinions 80 are keyed on the shaft 74 adjacent opposite sides of the conveyor frame 14 and adjacent the inner sides of the side plates 32. The drive pinions 80 mesh with the racks 42 for translationally moving the forwardly extending frame member 26 and gathering element 55 27 with respect thereto upon rotation of said drive pinions. Thus means have been provided for extending and retracting the gathering element 27, which means is movable with said gathering element and driven from the endless chains 19 of the flight conveyor 18. It may also be seen that as the gathering element 27 is moved with respect to the inclined conveyor frame 14, that the drive sprockets 24 and idler sprockets 23 move along the endless chains 19 and that the drive sprockets 24 may be driven from said endless chains when extended along said inclined conveyor.

Referring now in particular to the means for shifting the clutch member 66 and several other novel features of my invention, a clutch fork 81 is provided which has suitable pins extending inwardly from opposite sides of the prongs thereof. Said pins are engageable with a suitable groove formed in said outer periphery of the clutch member for shifting said clutch member.

The clutch fork 81 is supported for pivotal movement about an axis perpendicular to the longitudinal axis of the inclined conveyor frame 14 on members 85 at its top and bottom sides thereof.

A portion 86 of the clutch fork 81 extends inwardly therefrom and is engaged with a socket 87 provided in a link of an endless chain 88. The endless chain 88 extends longitudinally of the conveyor frame 14 and is trained around an idler sprocket 89 supported on the inclined conveyor frame 14 adjacent the forward end thereof. From thence said endless chain extends around a sprocket 90 supported on a shaft 91 journaled in the inclined conveyor frame 14 in a suitable manner (not herein shown). A hand wheel 93 is keyed on the outer end of the shaft 91 for rotating said shaft and the sprocket 90. Thus rotation of the hand wheel 93 in one direction or another drives the endless chain 88 which moves the socket 87 in one direction or another with respect to the inclined conveyor frame 14. Movement of the socket 87 in turn moves the rearwardly extending portion 86 of the clutch fork 81 which pivotally moves said clutch fork and shifts the clutch member 66 longitudinally 20 of the shaft 52. During movement of the gathering element 27 along the conveyor frame 14, the socket 87 is moved by the portion 86 of the clutch fork 81 which drives the endless chain 88 and rotates the hand wheel 93. It may be seen that the arrangement is such that the clutch member 66 may be shifted from a common point on said conveyor frame in any position of the gathering element 27 with respect to the inclined conveyor frame 14.

Suitable means are provided for automatically shifting the clutch member 66 when the gathering element 27 is in an extreme forward or rearward position with respect to the inclined conveyor frame 14, which means includes a stop 94. Said stop is formed integral with the outer side of the side plate 16 of the inclined conveyor frame 14 and disposed adjacent the forward end thereof and forwardly of the idler sprocket 89. A stop 95 is formed integral with the side plate 16 of the inclined conveyor frame 14 and is spaced rearwardly from the stop 94. Said stops are adapted to engage an inwardly extending projection 96 of a shifting member 97. Said inwardly extending projection of said shifting member rides in suitable guides in the side plates 32. Said shifting member is supported for slidable movement with respect to the side plates 32 in brackets 98. Said shifting member extends rearwardly and outwardly from said brackets and has a notch formed in the underside of its rearward end which is engageable with the clutch fork 81 for moving said clutch fork about its axis of pivotal connection to the forwardly extending frame member 26 and shifting the clutch member 66.

When the clutch jaws 67 are engaged with the clutch jaws 69, the gathering element 27 is moved forwardly along the inclined conveyor frame 14 at a relatively slow rate of speed by means of the pinions 80 meshing with the racks 42 and driven by the planetary gear reduction device 58. As the forwardly extending frame member 26 and gathering element 27 is moved forwardly along the inclined conveyor frame 14, and as said forwardly extending frame member reaches the end of its forward movement, the projection 96 of the shifting member 97 engages the stop 94. Engagement of the stop 94 with the projection 96 of the shifting member 97 will effect movement 75

of the shifting member 97 rearwardly with respect to the forwardly extending frame member 26 which will disengage the clutch jaws 67 from the clutch jaws 69. The clutch jaws 67 being disengaged from the clutch jaws 69, forward movement of the gathering element 27 along the inclined conveyor frame 14 is stopped and the clutch jaws 70 are engaged with the clutch jaws 71 to retract said gathering element by means 10 of the hand wheel 93 in a manner which has hereinbefore been described. When the clutch jaws 70 are engaged with the clutch jaws 71, the gathering element 27 and forwardly extending frame member 26 will move rearwardly along the 15 inclined conveyor frame 14 until the projection 96 of the shifting member 97 engages the stop 95. Engagement of the projection 96 with the stop 95 will move the shifting member 97 forwardly with respect to the forwardly extending frame member 26 which will disengage the clutch jaws 70 from the clutch jaws 71 and stop movement 20 of said forwardly extending frame member along the inclined conveyor frame 14.

It may thus be seen that means have been 25 provided for extending the gathering element 27 along the conveyor frame 14 at a relatively low rate of speed, which means is driven from the flight conveyor 18 and that said means may also effect withdrawal of said gathering element at a 30 higher rate of speed without reversal of movement of said flight conveyor. It may also be seen that automatic safety means have been provided to stop movement of the gathering element 27 along the conveyor frame 14 and prevent the 35 transversely extending frame member 26 from running off the inclined conveyor frame 14 and to limit rearward movement of said transversely extending frame member with respect to said inclined conveyor frame. It may also be seen that 40 the device of my invention is so arranged that the means for extending and retracting the gathering element 27 may be controlled from a common point on the inclined conveyor frame 14 in all positions of travel of said gathering element 45 with respect to said inclined conveyor frame, and that the mechanism for moving said gathering element along said conveyor frame travels along the conveyor 18 and endless chains 19 while being driven therefrom during movement of said 50 gathering element along said conveyor frame.

While I have herein shown and described one form in which my invention may be embodied, it will be understood that the construction and arrangement of the various parts may be altered 55 or changed without departing from the spirit or scope thereof. Furthermore, I do not wish to be construed as limiting myself to the particular embodiment illustrated, excepting as it may be limited in the appended claims.

60 I claim as my invention:

1. In combination with a loading machine, an inclined conveyor comprising a conveyor frame and a plurality of endless chains having flights carried therebetween, a gathering element supported on said inclined conveyor for slidable movement therealong, and means carried by said gathering element and movable along and driven by said endless chains for moving said gathering element along said inclined conveyor 65 comprising a pinion, a rack meshed with said pinion, and gear reduction mechanism driven by said endless chains and having driving connection with said pinion.

2. In combination with a loading machine, an 70 inclined conveyor comprising a conveyor frame 75

and a plurality of endless chains having flights carried therebetween, a gathering element supported on said inclined conveyor for slidable movement therealong, means supported on said gathering element and movable along and driven by said endless chains for moving said gathering element forwardly along said inclined conveyor at a relatively slow rate of speed and rearwardly along said inclined conveyor at a higher rate of speed without reversal of said 10 endless chains.

3. In combination with a loading machine, an inclined conveyor comprising a conveyor frame and a plurality of endless chains having flights carried therebetween, a gathering element supported on said inclined conveyor for slidable movement therealong, means carried by said gathering element and movable along and driven by said endless chains for moving said gathering element along said inclined conveyor including means for automatically stopping movement of said gathering element along said inclined conveyor at either the forward or rearward extremities thereof while said endless chains are moving in one direction.

4. In combination with a loading machine, a conveyor comprising a conveyor frame and a plurality of endless chains having flights carried therebetween, a gathering element supported on said conveyor for reciprocable slidable movement therealong, means supported on said gathering element and movable along and driven by said endless chains for moving said gathering element forwardly along said conveyor at a slow rate of speed and rearwardly along said conveyor at a higher rate of speed without reversal of said endless chains, means for controlling movement of said gathering element along said conveyor from a common point on said conveyor in all positions of said gathering element with respect to said conveyor and means for automatically stopping rearward or forward movement of said gathering element along said conveyor at either the forward or rearward extremities thereof.

5. In combination with a loading machine, a conveyor, a gathering element supported on said conveyor for reciprocable slidable movement therealong, and means driven by said conveyor for moving said gathering element therealong comprising a shaft extending parallel with said conveyor and driven thereby, a rack, a pinion meshing with said rack, and means driven by said shaft for driving said pinion in one direction at one speed and in another direction at another speed without reversal of rotation of said shaft.

6. In combination with a loading machine, a conveyor, a gathering element supported on said conveyor for reciprocable slidable movement therealong, means driven by said conveyor for moving said gathering element therealong comprising a shaft extending parallel with said conveyor and driven thereby, a rack, a pinion meshing with said rack, and means driven by said shaft for driving said pinion in one direction at one speed and in another direction at another speed without reversal of rotation of said shaft comprising a planetary gear reduction device.

7. In combination with a loading machine, a conveyor, a gathering element supported on said conveyor for reciprocable slidable movement therealong, means driven by said conveyor for moving said gathering element therealong com-

slidable movement therealong, and means driven by said inclined conveyor for moving said gathering element therealong comprising a shaft extending parallel with said inclined conveyor and driven thereby, a rack, a pinion meshing with said rack, and means driven by said shaft for driving said pinion in one direction at one speed and in another direction at another speed without reversal of rotation of said shaft comprising a planetary gear reduction device including a casing having an internal gear connected thereto, a sun gear rotated by said shaft, planetary pinions meshing with said sun gear and internal gear and movable about said sun gear, means for holding said planetary pinions from orbital movement with respect to said sun gear or orbitally moving said planetary pinions with said sun gear comprising a clutch member connectible with said planetary pinions and shiftable along said shaft for engagement with a fixed non-rotatable part or suitable means on said shaft, means for shifting said clutch member from a single point on said inclined conveyor frame during any position of movement of said gathering element with respect to said conveyor frame, and other means connectible with said inclined conveyor and clutch member for automatically shifting said clutch member as said gathering element approaches either the forward or rearward extremities of its travel along said inclined conveyor.

14. In combination with a loading machine, an inclined conveyor, a gathering element supported on said inclined conveyor for reciprocable slid- able movement therealong, means driven by said inclined conveyor for moving said gathering element therealong comprising a shaft extending parallel with said inclined conveyor and driven thereby, a rack, a pinion meshing with said rack, and means driven by said shaft for driving said pinion in one direction at one speed and in another direction at another speed without reversal of rotation of said shaft comprising a planetary gear reduction device including a casing having an internal gear connected thereto, a sun gear rotated by said shaft, planetary pinions meshing with said sun gear and internal gear and movable about said sun gear and means for holding said planetary pinions from orbital movement with respect to said sun gear or orbitally moving said planetary pinions with said sun gear comprising a clutch member connectible with said planetary pinions and shiftable along said shaft for engagement with a fixed non-rotatable part or suitable means on said shaft, means for shifting said clutch member from a single point on said inclined conveyor frame during any position of movement of said gathering element with respect to said conveyor frame comprising an endless chain threaded about a suitable drive means on said inclined conveyor frame having operative connections with said clutch member and means connectible with said drive means for operating said endless chain, and other means connectible with said inclined conveyor and clutch member for automatically shifting said clutch member as said gathering element approaches either the forward or rearward extremities of its travel along said inclined conveyor.

15. In combination with a loading machine, an inclined conveyor comprising a conveyor frame, a gathering element carried for movement therealong, drive sprockets adjacent the rearward end of said conveyor frame, direction changing devices adjacent the forward end of said conveyor frame and endless chains having flights carried

therebetween trained around said drive sprockets and direction changing devices for continuous movement thereabout, and means supported by said inclined conveyor and movable along said endless chains for moving said gathering element forwardly or rearwardly along said inclined conveyor comprising a shaft extending parallel with and driven by said endless chains, a rack, a pinion meshing with said rack, and means driven by said shaft for driving said pinion in one direction at one speed and in another direction at another speed without reversal of rotation of said shaft.

16. In combination with a loading machine, an inclined conveyor comprising a conveyor frame, a gathering element carried for movement therealong, drive sprockets adjacent the rearward end of said conveyor frame, direction changing devices adjacent the forward end of said conveyor frame and endless chains having flights carried therebetween trained around said drive sprockets and direction changing devices for continuous movement thereabout, and means supported by said inclined conveyor and movable along said endless chains for moving said gathering element forwardly or rearwardly along said inclined conveyor comprising a shaft extending parallel with and driven by said endless chains, a rack, a pinion meshing with said rack, and means driven by said shaft for driving said pinion in one direction at one speed and in another direction at another speed without reversal of rotation of said shaft comprising a planetary gear reduction device including a plurality of orbitally movable planetary pinions and means for holding said planetary pinions from orbital movement or allowing said planetary pinions to move in orbital paths about the axis of said shaft.

17. In combination with a loading machine, an inclined conveyor comprising a conveyor frame, a gathering element carried for movement therealong, drive sprockets adjacent the rearward end of said conveyor frame, direction changing devices adjacent the forward end of said conveyor frame and endless chains having flights carried therebetween trained around said drive sprockets and direction changing devices for continuous movement thereabout, and means supported by said inclined conveyor and movable along said endless chains for moving said gathering element forwardly or rearwardly along said inclined conveyor comprising a shaft extending parallel with and driven by said endless chains, a rack, a pinion meshing with said rack, and means driven by said shaft for driving said pinion in one direction at one speed and in another direction at another speed without reversal of rotation of said shaft comprising a planetary gear reduction device including a plurality of orbitally movable planetary pinions and means for holding said planetary pinions from orbital movement or allowing said planetary pinions to move in orbital paths about the axis of said shaft comprising a clutch member connectible with said planetary pinions and shiftable along said shaft for engagement with a fixed non-rotatable part or suitable means on said shaft.

18. In combination with a loading machine, a conveyor, a gathering element supported on said conveyor for reciprocable slid- able movement therealong, and means driven by said conveyor for moving said gathering element along said conveyor in a forwardly direction with respect to said conveyor at a slow speed and in a rearwardly direction at a higher speed comprising a shaft driven by said conveyor, drive means connectible with

- 5 said gathering element and conveyor for moving said gathering element along said conveyor, means connecting said shaft with said drive means for driving said drive means in one direction at one speed and in another direction at another speed comprising a clutch member, and means for shifting said clutch member from a single point on said conveyor during any position of movement of said gathering element with respect to said conveyor.
- 10 19. In combination with a loading machine, a conveyor, a gathering element supported on said conveyor for reciprocable slidable movement therealong, and means driven by said conveyor for moving said gathering element along said conveyor in a forwardly direction with respect to said conveyor at a slow speed and in a rearwardly direction at a higher speed comprising a shaft driven by said conveyor, drive means connectible with said gathering element and conveyor for moving said gathering element along said conveyor, means connecting said shaft with said drive means for driving said drive means in one direction at one speed and in another direction at another speed comprising a clutch member, and means for shifting said clutch member from a single point on said conveyor during any position of movement of said gathering element with respect to said conveyor comprising flexible power transmission means supported by said conveyor and having operative connection with said clutch member, and means on said conveyor for driving said flexible power transmission means.
- 15 20. In combination with a loading machine, an inclined conveyor, a gathering element supported on said inclined conveyor for reciprocable slidable movement therealong, and means driven by said inclined conveyor for moving said gathering element along said inclined conveyor in a forwardly direction with respect to said inclined conveyor at a slow speed and in a rearwardly direction at a higher speed comprising a shaft driven by said conveyor, drive means connectible with said gathering element and inclined conveyor for moving said gathering element along said inclined conveyor, means connecting said shaft with said drive means for driving said drive means in one direction at one speed and in another direction at another speed comprising a clutch member, and means for shifting said clutch member from a single point on said inclined conveyor during any position of movement of said gathering element with respect to said inclined conveyor comprising flexible power transmission means supported by said inclined conveyor and having operative connection with said clutch member, and means on said inclined conveyor for driving said flexible power transmission means, and other means connectible with said inclined conveyor and clutch member for automatically shifting said clutch member as said gathering element approaches either the forward or rearward extremities of its travel along said inclined conveyor.
- 20 21. In an extensible conveying means, a frame
- 25 having a conveyor thereon, a conveying element mounted on said frame for slidable movement therealong and adapted to discharge material onto said conveyor, and means carried by said conveying element and movable along and driven by said conveyor for moving said conveying element along said frame while being driven by said conveyor comprising a pinion, a rack meshed with said pinion, a drive connection from said conveyor to said conveying element and a selective drive connection from said last-named drive connection to said pinion.
- 30 22. In an extensible conveying means, a frame having a conveyor thereon, a conveying element on said frame and slidably movable with respect thereto and adapted to discharge material onto said conveyor, and means carried by said conveying element and movable along and driven by said conveyor for moving said conveying element along said frame while being driven by said conveyor comprising a pinion, a rack meshed with said pinion, a drive connection from said conveyor to said conveying element and a selective reversible drive connection from said last-named drive connection to said pinion.
- 35 23. In an extensible conveying means, a frame having a conveyor thereon, a conveying element on said frame and slidably movable with respect thereto, and means carried by said conveying element and movable along and driven by said conveyor for moving said conveying element along said frame while being driven by said conveyor comprising a pinion, a rack meshed with said pinion, a drive connection from said conveyor to said conveying element and a selective reversible drive connection from said last-named drive connection to said pinion including a planetary geared reduction device.
- 40 24. In an extensible conveying means, a frame having a conveyor thereon, a conveying element mounted on said frame for slidable movement with respect thereto and adapted to discharge material onto said conveyor, and means carried by said conveying element and movable along and driven by said conveyor for moving said conveying element along said frame at a relatively slow rate of speed in one direction and at a higher rate of speed in an opposite direction without reversal of said conveyor while being driven by said conveyor.
- 45 25. In an extensible conveying means, a frame having a conveyor thereon, a conveying element on said frame and slidably movable with respect thereto, means carried by said conveying element and movable along and driven by said conveyor for driving said conveying element along said frame while being driven by said conveyor including reverse drive mechanism comprising a planetary geared reduction device, and means for automatically stopping movement of said conveying element along said frame at either the forward or rearward extremities thereof while said conveyor is moving in one direction.
